ELECTRICAL CONTROL DEVICE

Harry A. Douglas, Bronsen, Mich., assignor to
 Kingston Products Corporation, a corporation
 of Indiana

Application February 26, 1935, Serial No. 8,316

5 Claims. (Cl. 200—166)

My invention relates to electrical control devices and to electrical contact and terminal means which may form a part of electrical control devices. One of the uses to which my invention may be put is in connection with electric switches and the like, and a more specific use is in connection with the control of electrical resistances. The principal object of my invention is to provide new and improved electrical devices and means of the hereinbefore mentioned types. In the drawing accompanying this specification, and forming a part of this application, I have shown, for purposes of illustration, one form which my invention may assume. In the drawing:

Figure 1 is a vertical sectional view of one embodiment of my invention as it may be applied in a resistance control switch.

Figure 2 is a rear elevation of the base of the switch shown in Figure 1, with contact means and a resistor assembled therewith.

Figure 3 is a fragmentary sectional view taken along the line 3—3 of Figure 2, looking in the direction of the arrows.

Figure 4 is a fragmentary sectional view taken along the line 4—4 of Figure 2, looking in the direction of the arrows, and

Figure 5 is a perspective view of a detail, with certain parts disassembled.

Referring to Figure 1 of the drawing a panel 10 has mounted thereon a switch casing 11, of cup-shape, having a bottom 12 and a tubular portion 13 extending therefrom. Fastened to the bottom 12 in any suitable manner is a threaded nipple 14 extending through an aperture in the panel 10, and engaged by a nut 15. A shaft 16 is disposed through the nipple 14 and is provided at one end with an operating handle 17. At the other end the shaft 16 is provided with a laterally extending member 18 drivingly connected in any suitable manner to an insulating carrier 19.

The insulating carrier 19 carries a contact member 20 which may be of any suitable form and in this instance is shown as extending from the center of the face of the contact carrier 19 to the radially outer edge thereof, as indicated by the dotted lines 20 in Figure 2. The contact 20 may be provided with depressions, one of which, 21, is visible in Figure 1, these depressions being provided for cooperation with relatively stationary contact means mounted on a base 22. The base 22 is adapted to be received by the open end of the casing 11, and fastened to the casing 11 in any suitable manner.

The base 22 is provided with a generally cen-

tral boss 23, in which is reciprocably mounted a contact means 24, having a construction substantially similar to that disclosed in my copending application Serial Number 8,315, filed February 26, 1935; since formally abandoned in favor of my 5 substitute co-pending application, Serial Number 205,299, filed April 30, 1938. The contact means 24 is here shown of U-shape and desirably formed to that shape from sheet stock, which may be iron, steel, or other suitable metal. The U-shaped 10 contact means 24 has legs 25, 26, the leg 25 being adapted to be received in an aperture 27, extending axially through the base 22 and the boss 23 thereof. The leg 26 is adapted to be received in an aperture 28, extending through the 15 base 22 and the boss 23 thereof. As will be seen from Figure 2, the apertures 27, 28 are parallel to each other and at right angles to a diameter of the base 22. Also, the aperture 27 is wider than the aperture 28, and both apertures 20 conform in cross-section and position so as to reciprocably receive the legs 25, 26 of the U-shaped contact means 24.

The apertures 27, 28 are connected, at the inner face of the base 22, by a recess 29 extending from the inner face of the base 22 part way into the boss 23 and terminating in a bottom 30. The width of the recess 29, as viewed in Figure 2, may be the same as that of the aperture 28.

The contact means 24 carries a contact 31, 30 adapted to cooperate with the depression 21 in the contact 20. The contact 31 is formed similarly to a rivet, the head serving to provide an electrical contact surface and the shank passing through an aperture in the bight of the U-shaped 35 contact means 24. The end of the shank of the contact 31 is upset or riveted and forms a projection 32, which also serves to position or locate one end of a spring 33, the other end of which bears against the bottom 30 of the recess 29. 40

The contact means 24 is provided with conductor terminal connecting means comprising a screw 34 cooperating with a threaded hole in the leg 25, the leg 25 being longer than the leg 26 and extending away from the outer face of the 45 boss 23. A conductor 36 is here shown as clamped between the head of the screw 34 and a lock washer 35, although the conductor 36 may be interposed between the washer 35 and the leg 25. The washer 35 is provided at the periphery of 50 its central aperture with serrations 37, extending laterally from both faces of the washer. The washer 35 is also provided with a lateral projection 38 adapted to extend through a hole 39 in the leg 25, to thereby prevent turning of the 55

washer. The lateral extension 38 may also serve to limit motion of the contact means 24 to the right as viewed in Figure 1, by engagement of the projection 38 with a shoulder 40 cut back from the outer face of the boss 23.

The boss 23, as may be seen in Figure 2, has an arcuate generally axially extending surface 41 concentric with the base, bounding a portion of the transverse section of the boss, and another arcuate surface 42 of greater radius than the arcuate surface 41, also concentric with the base, and merging in any suitable way with the arcuate surface 41. The arcuate surface 42 serves to form the radially inner side of an arcuate recess 43 in the outer face of the base 22. As shown in Figure 1, the recess 43 has a bottom 44 arcuate in radial cross-section. The radially outer side 45 of the recess 43 is formed in part by the inner periphery of an axially extending arcuate flange 46 provided on the base 22. The terminal ends 47 of the arcuate recess 43 are formed by bosses 47, 48 on the base 22.

A resistor 49 is disposed in the arcuate recess 43, the resistor 49 comprising in this instance a helical resistance wire flexed to arcuate form and having terminal ends 50, 51 connected to contact means 52, 53 respectively.

The contact means 52, shown in detail in Figure 3, is reciprocably mounted in the boss 47 and comprises a body portion 54 of suitable metal. The body portion 54 has an axial bore 55 extending from one end thereof a desired distance toward the other end, and a transverse aperture 56 near the other end. The bore 55 communicates with the transverse aperture 56, the bore 55 being constricted at the point of communication to form a seat 57 for a ball 58.

The body portion 54 of the contact means 52 is oblong in cross-section, the transverse aperture 56 having its axis extending approximately along a diagonal of the oblong cross-section, as may be seen in Figure 2. The corners of the body portion 54 are chamfered to form four rounded surfaces 59. The chamfers 59 do not extend the entire length of the body 54, but terminate near one end of the body 54 to thereby form four shoulders 60, as may be seen most clearly in Figure 5. The shoulders 60 serve the purpose of retaining at the open end of the axial bore 55 an end closure 61. The end closure 61 is here shown as comprising a dome-shaped portion 80 merging into a radially extending flange 81 from which extends in an axial direction a cylindrical flange 62. The inside diameter of the cylindrical flange 62 is desirably of the same diameter initially as the diameter of a circle circumscribing the apexes of the four shoulders 60. The radially extending flange 81 is adapted to abut the right hand end of the body 54, as viewed in Figure 3, and the peripheral edge 60 of the flange 62 is spun radially inwards around the projections formed by the shoulders 60, and against the shoulders 60, thereby securely fastening the end closure 61 to the body 54. The dome-shaped portion 80 of the end closure serves to 65 provide a contact surface, and if desired the closure 61 may be made of a different metal from the body 54, a desirable metal being brass.

Within the bore 55 of the body 54 is disposed a helical spring 63, one end of which engages the end closure 61 and the other end of which engages the ball 58, thereby biasing the ball toward the seat 57.

The body 54 of the contact means 52 is adapted to be reciprocably received in an aperture 64 in the boss 47, the aperture 64 being of the same

shape as the cross-sectional shape of the body 54. The aperture 64 is countersunk by a recess 65, extending from the inner face of the boss 22, through the base proper and part way into the boss 47 thereof. Disposed about the body 54 is a helical spring 66, one end of which bears against the spun over portion of the flange 62 and the other end of which bears against the bottom of the recess 65.

A conductor terminal 67 is here shown in co-operative relation with the aperture 64 in the body 54, the conductor terminal 67 being provided with an annular furrow 68, into which the ball 58 is urged by the spring 63. The end of the conductor terminal 67 is here shown as having a frusto-conical end, which is swaged to the conductor within the terminal 67, as indicated by the wedge indentations 70.

Extending axially from the end of the body 54 is a stud 71 of cylindrical contour and less in cross-section than the body 54. The stud 71 is provided with an axially extending diametrical slot 72, the walls of this slot being spaced such distance as to receive and hold the terminal 50 of the resistor 49. The halves of the stud 71 may be bent toward each other so as to pinch the terminal 50 between the walls of the slot 72, as shown most clearly in Figure 5. In the embodiment illustrated, when the contact means is assembled with the base 22, the slot 72 is vertical, as viewed in Figure 2, as is also the axis of the conductor terminal receiving aperture 64. The slot 72 thus is substantially on a diagonal of the cross-section of the body 54.

The contact means 53 comprises a body portion 73, of oblong cross-section similar to that described in connection with the body of the contact means 52, and has an axial bore 74 terminating short of one end of the body 73. The body 73 is chamfered in the same manner as already described in connection with the contact means 52, leaving four shoulders 77, which serve as a means of attaching an end closure 78, identical with the end closure 61, to the body 73, by spinning a flange 76, the same as the flange 62 of the end closure 61, over the shoulders 77.

The contact means 53 is reciprocably mounted in the boss 48, an aperture 78 in the boss 48 being formed to receive the body 73. The cross-section of the aperture 78 is of the same form as the cross-section of the body 73. The body 73 is provided with an axially extending stud 79 having a slot 82 formed therein in a manner similar to that of the slot 72 in the stud 71. The slot 82 is adapted to receive the terminal 51 of the resistor 49, and the halves of the stud 79 may be bent toward each other, so as to pinch the terminal 51, as already described in connection with the terminal 50.

In the disclosed embodiment no connection to an external conductor terminal, such as the terminal 67, is necessary in connection with the contact means 53, and consequently, the contact means 53 does not include a snap terminal means comprising a ball 58 and a transverse aperture 56, such as described in connection with the contact means 52. However, the contact means 53 also has disposed around the body 73 a helical spring 83 adapted to be received in a recess 84 corresponding to the recess 65. One end of the spring 83 bears against an end of the flange 76 and the other end bears against the bottom of the recess 84.

It will be evident that the contact means 52, 53, while performing the function of cooperating

with the relatively movable contact element 20, also perform the function of making electrical connection to the resistor 49 and mechanically supporting it in the recess 43.

5 When the parts are assembled as shown in Figure 1, the contact means 24, 52, and 53 are biased toward the contact carrier 19, the contact 31 remaining in contact with the depression 21 of the contact 20 in any position of the operating handle 17, whereas the contact elements 61, 75 are either in contact with a depression, similar to the depression 21, in the radial end of a contact 20, or in contact with a depression in the insulating carrier 19 itself. Thus, in the position of the 10 parts shown in Figure 2, a circuit would be established from the conductor terminal 67 to the terminal 50 of the resistor, through the resistor 49 to the terminal 51 thereof, through the contact means 53, to and through the contact 20, through 15 the contact means 24, to the conductor 36. On the other hand, if the handle 17 is thrown so that the radial end of the contact 20 contacts with the contact element 61, a circuit is established from the conductor terminal 67, through 20 the contact means 52, through the contact 20, through the contact means 24, to the conductor 36, thereby eliminating the resistor 49 from the circuit.

In view of the foregoing it will be obvious 30 to those skilled in the art that my invention may be embodied in other constructions wherein the elements may assume a variety of forms, variously changed and modified within the spirit of the invention.

35 In general it will be clear to those skilled in the art that the features of my invention need not all be used in one embodiment, and may be individually or collectively variously changed and modified, without departing from the spirit of the invention, or sacrificing all of the advantages 40 thereof, and particularly, that my invention is not limited to conductor terminals of the plug type, but that the term conductor terminal is to be considered generic, including for example 45 merely a portion of the conductor wire itself, and accordingly that the disclosure herein is illustrative only, and that my invention is not limited thereto.

I claim:

50 1. In combination: a solid metallic body portion having a longitudinal bore and a transverse bore, said longitudinal bore opening to one end of said body portion and having a portion reduced in size inwardly of said body and communicating 55 with said transverse bore through said reduced portion, said body being of polygonal cross-sectional outline, having a predetermined number of its longitudinal corners chamfered to form shoulders near one end of said body portion; contact means spanning the open end of said longitudinal bore, and including a circular flange interengageable with said body portion shoulders; and resilient detent means interposed between

said contact means and the reduced portion of said longitudinal bore, said detent means having a part cooperable with the transverse aperture and being operable to yieldably engage and hold a conductor terminal disposable within said transverse aperture. 5

2. Terminal means, comprising: a metallic body, having a longitudinal aperture entering from one end, and being formed with a plurality of laterally extending projections adjacent said one end, said body also having a transverse aperture communicating with said longitudinal aperture and being adapted to receive a conductor terminal; a contact member, having a cylindrical flange circumscribing said laterally extending 10 projections, the extremity of said flange being crimped over said projections to hold said contact member to said body; and biasing means within said longitudinal bore, having one end bearing against said contact member, and its other end 15 in position to yieldably engage a conductor terminal disposed within said transverse aperture.

3. Terminal means, comprising: a metallic body, having a reduced integral projection at one end, said projection being bifurcated to receive an 20 electrical conductor, and said furcations being adapted to be clinched together to hold said conductor, said body having laterally extending projections adjacent its other end; contact means, having a cylindrical flange circumscribing said 25 projections, the extremity of said flange being crimped over said projections to mechanically and electrically hold said body and said contact means in assembled relation. 30

4. Terminal means, comprising: a body, having 35 a longitudinal aperture entering from one end, and formed with laterally extending shoulder means at said one end, said body having also a transverse aperture communicating with said longitudinal aperture, and being adapted to receive a 40 conductor terminal; a contact member, having a surface abutting said one end of said body, and having also a marginal flange, the free extremity of which is bent to overlie said shoulder means, so that said contact member is held against 45 movement longitudinally of said body.

5. Terminal means, comprising: a body, having a longitudinal aperture entering from one end, and formed with laterally extending shoulder means at said one end, said body having also a 50 transverse aperture communicating with said longitudinal aperture, and being adapted to receive a conductor terminal; a contact member, having a marginal flange, the free extremity of which is bent to overlie said shoulder means, holding said 55 contact member assembled with said body; and biasing means, disposed within said longitudinal aperture, having one end bearing against the adjacent surface of said contact member, and its other end in position to yieldably engage a conductor terminal disposed in said transverse aperture. 60

HARRY A. DOUGLAS.
